ILLUMINATED SIGN

Paul J. Scharringhausen, Des Plaines, Ill.

Application December 24, 1930
Serial No. 504,478

9 Claims. (Cl. 40—130)

Signs of the luminescent-tube type, such as neon-tube and argon-tube signs, have become extraordinarily popular notwithstanding their relatively high cost and the impossibility of modifying a given sign so as to display various messages to the public.

The object of the present invention is to produce a luminescent-tube sign which shall possess the attractiveness of the luminescent-tube signs of the prior art, which shall be comparatively inexpensive, and which shall be adapted to be readily and economically changed so as to display any desired message to the beholder. This object has been attained by utilizing a luminescent tube for the purpose of transmitting light through the edges of a glass plate and by applying the desired inscription upon the surface of the glass plate by means of crayon, crayola, or equivalent material, the light transmitted from the luminescent tube through the glass plate causing the inscription to glow in a manner simulating the appearance of a luminescent-tube sign.

In the accompanying drawing:

Figure 1 is a sectional view of a sign embodying the features of my invention, the view being taken in the plane of dotted line 1—1 of Fig. 2.

Fig. 2 is a section taken in the plane of line 2—2 of Fig. 1.

The embodiment which has been selected to illustrate the invention comprises a rectangular frame surrounding an edge illuminated glass plate, but it will be understood that the frame may be of any other desired outline. In the construction herein shown, the frame comprises two rectangular halves or sections 1 and 2 arranged to be secured together by any suitable means, as, for example, screws 3. Said frame surrounds and supports a double-faced inscription-displaying structure, herein shown as consisting of two smooth transparent colorless glass plates 4 arranged side by side with an opaque backing 5 between them. This backing may consist of a coating of paint or the like, preferably black, or a sheet of black paper, or any other desired material having a so-called matt or non-reflecting surface. As shown in Fig. 2, the frame sections 1 and 2 are rabbed upon their opposed faces so as to provide a groove 6 extending entirely around the inner edge of the frame to receive the edges of the plates 4 and the backing 5.

Enclosed within the frame is a luminescent tube 7 located in the plane of the glass plates 4 so as to transmit light through the edges of said plates. Herein I have shown the frame as formed

to provide a chamber 8 extending around the glass plates 4, the edges of said plates being exposed within said chamber. Preferably, the walls of the chamber 8 are provided with a reflecting surface, as, for example, by applying thereto a 60 coating 9 of white paint or other suitable material.

If desired, the chamber 8 may contain two luminescent tubes. In the construction herein shown there is a tube 10 in addition to the tube 7, both tubes extending entirely around the glass 65 plates and lying in the same plane. These tubes may be supported within the chamber 8 in any preferred manner, as by means of brackets 11.

The lower, or any other convenient portion of the frame, may be provided with a chamber 12 70 to house the electrodes of the luminescent tube or tubes. The electrodes of each tube are connected into an electric circuit in the usual or any preferred manner. Where a plurality of tubes are used, one may be filled with neon gas and 75 another with argon gas, the tubes being alternately energized by means of a flasher of ordinary construction.

The message to be displayed by means of the sign may be written upon the outer surfaces of 80 the glass plates 4 by means of crayon, crayola, "Bon Ami", or other material. The material used may be white or of the same color or colors as that produced by the luminescent tube or tubes, and is preferably, translucent.

When the tube or tubes are not energized it will be evident that the inscriptions upon the glass plates 4 may be read against the opaque background afforded by the backing 5 when the sign is exteriorly illuminated by daylight or other 90 suitable means. When the tube or tubes are in operation, the letters, symbols, pictures, or other designs applied to the glass plates are illuminated by the light transmitted from the luminescent tube through the edges of the glass plates, the 95 inscriptions being caused to glow with the color of the light produced by the tube so that at a distance the inscription has essentially the same appearance as an ordinary neon or argon sign but without the objectionable light-intensity of 100 the latter.

It will be seen that by reason of the manner in which the message to be displayed is applied to the glass, the message may be easily erased, after the manner of an inscription upon a slate, 105 and a different inscription placed thereon, thus making the sign particularly useful to merchants or others who desire to make frequent changes in their advertisements.

While I have shown a double-faced sign, it 110

will be evident that the invention may be embodied in a single-faced sign.

The term "writing" in the following claims is intended to include the application of "Bon Ami" or other suitable substances by means of a brush.

I claim as my invention:

1. An illuminated sign comprising a plate of light pervious material having a smooth surface, means arranged to transmit light through an edge of said plate and a readily applied and removable inscription of translucent material on the smooth surface of said plate.

2. An illuminated sign comprising a glass plate having smooth surfaces, luminescent tubing arranged to transmit light through the edges of said plate and a readily applied and removable inscription of translucent material on a smooth surface of said plate.

3. In an illuminated sign, a smooth surfaced glass plate, means arranged to transmit light into said glass plate angularly with respect to the smooth surfaces thereof whereby the light is reflected back and forth between the smooth surfaces of said glass plate in passing substantially edgewise through the plate and a readily applied and removable inscription of translucent material upon the smooth surface of said plate adapted to be rendered luminous by dispersion of light received from said glass plate.

4. In an illuminated sign, a smooth surfaced glass plate, an opaque backing on one of the smooth surfaces of said plate, means arranged to transmit light into said plate angularly with respect to the smooth surfaces thereof, whereby the light is reflected back and forth between the smooth surfaces of said glass plate in passing substantially edgewise through the plate and a readily applied and removable inscription on the smooth front surface of the plate adapted to be rendered luminous by dispersion of light received from said glass plate.

5. An illuminated sign comprising a glass plate having smooth surfaces, an opaque backing for said plate, luminescent tubing arranged to transmit light through the edges of said glass plate

and a readily applied and removable inscription of translucent material on the smooth front surface of said plate.

6. An illuminated sign comprising a plate of light pervious material having smooth inner and outer surfaces, means for transmitting light substantially edgewise through said plate, an opaque non-reflecting backing for said plate and a readily applied and removable inscription of translucent material on one of the smooth surfaces of said plate and having a contrasting color with respect to said backing.

7. An illuminated sign comprising a plate of light pervious material having smooth inner and outer surfaces, an opaque non-reflecting backing for said plate, means for transmitting light substantially through the entire peripheral edge of said plate and a readily applied and removable inscription of translucent material on the smooth outer surface of said plate having a contrasting color with respect to said backing whereby light transmitted edgewise through said plate is dispersed to produce luminescence of said inscription.

8. An illuminated sign comprising a pair of plates of light pervious material arranged side by side, said plates having continuously smooth inner and outer surfaces, an opaque non-reflecting backing between said plates, a luminescent tube extending substantially entirely around the peripheral edges of said plates and a readily applied and removable inscription of translucent material on the smooth outer surfaces of said plates having a contrasting color with respect to said backing and adapted to be rendered luminous through the effect of the edgewise illumination.

9. The method of producing and displaying an illuminated advertisement which consists in transmitting light edgewise through a smooth surfaced light pervious plate and removably applying to a smooth surface of the plate a substance in the form of characters capable of becoming luminescent from the effect of light obtained from the interior of the plate.
